UNITED STATES PATENT OFFICE.

EDWARD R. KNOWLES, OF BROOKLYN, NEW YORK, ASSIGNOR OF ONE-HALF TO BYRON A. BROOKS, OF SAME PLACE.

ELECTRIC LAMP.

SPECIFICATION forming part of Letters Patent No. 288,346, dated November 13, 1883.

Application filed July 13, 1882. (No model.)

To all whom it may concern:

Be it known that I, EDWARD R. KNOWLES, of Brooklyn, in the county of Kings and State of New York, have invented certain new and useful Improvements in Electric Lamps, of which the following is a description in such full, clear, concise, and exact terms as to enable any one skilled in the art to which my invention appertains or with which it is most nearly connected to make and use the same, reference being had to the accompanying drawings, making part of this specification, in which—

Figure 1 is a vertical section through a completed lamp having my improvements applied thereto, and Figs. 2, 3, 4, 5, 6, 7 are parts in detail, to be hereinafter described.

My invention consists of certain mechanical improvements in the construction of the lamp and in the application of the circuits thereto.

The construction of the lamp and its machinery will be readily understood from the following description, and the points of novelty constituting my improvements will be designated in the claims concluding this specification.

Reference being had to the drawings, A and A' are two electro-magnets mounted on the frame E. The magnet A' is divided into sections 1 2 3 4, each of which is coiled full of wire wound in the same way, the inside ends of all the coils being joined together, as are also all the outside ends, making the quantitative magnet of Professor Henry. It is known that the power of a magnet depends upon the size of the wire with which it is wound and the number of convolutions within certain limits. When a magnet is coiled with a coarse wire, the convolutions do not fill all the space-stock the same as if wound with a fine wire; but by taking a number of small wires the sum of whose areas equals that of a given coarse wire, and winding each one on separately, and then connecting their ends as described, a much greater number of convolutions can be put over the magnet, while the total metal area will be the same, so that a much greater magnetic effect can be obtained by this arrangement of fine wire than by the ordinary winding with coarse wire. This magnet as such is not new; but by combining it in the lighting-circuit of an electric lamp, to work its ma-

chinery, a much smaller magnet can be used, while at the same time much greater magnetic force can be obtained and the resistance 55 of the circuit materially decreased.

The magnet A is wound with very fine wire, and the two magnets A and A' are connected, so that a differential action is set up, the magnetism of A pulling against the magnetism of 60 A', the two being so connected in circuit that about one per cent. of the current passes through A and all the rest through A'.

G is a rocking lever, connected at its ends to the movable magnet-cores B and B' by pins 65 P' and P'', passing through oblong holes J and J'', made in the ends of the lever. Said lever is also pivoted to the frame E at P'' through an oblong hole, J', in said lever. The ends of this lever embrace the ends of the cores B and 70 B', and through it the rod D also passes, as shown in Fig. 4.

D is a rod that carries the upper-carbon holder H' and carbons C', held by means of screw S''. The rod D passes through long cylindrical bearings H H, forming part of the frame E, and also through the lever G, as above described.

Pivoted in the lever G at P is a clutch-lever, F, the end of which carries a hollow receptacle, M, supplied with mercury, the amount of which can be adjusted to the weight required on the lever, the end of the lever being prevented from rising up above the lever G by a stop, 9, in the manner shown. S' is a set-screw, against which the weight M abuts when the lamp is not in action, the object of which is to release the rod D from the clutch-lever F the moment the circuit is disrupted. The object of this arrangement of the lever G with 90 the magnet-cores B and B' and the other connecting parts is to work or operate the upper carbon, as will be hereinafter explained. Modifications of substantially the same combination of devices for the same purpose are 95 shown by Figs. 5, 6, and 7 of the drawings. S''' and S'' are two adjustable contact-points insulated from E and G, and tipped with platinum 5 and 6.

In the top of the lamp-case K is inserted a 100 tube, U, in the top of which a ring, R'', is inserted, by which the lamp is suspended. Inside of the tube U a weight, V, is placed in the form of a ring, and made to embrace the

rod D. This weight is arranged to slide freely up and down in the tube and upon the rod, to which it is attached, by means of cords or chains C C, passing over pulleys 7 and 8, the object of the weight being to counterbalance the weight of the rod D. By these means much less magnetic force is made necessary to operate the upper electrode and its holder, for its weight being balanced by the weight V, to a very small magnet is all that is necessary to operate it.

The frame E, that carries the magnets A and A' and the rocking lever G, is secured to the frame L by the screws S S. To the upper-carbon holder H' is attached a catch-hook, 11, and to the lower side of the lamp-frame L is bolted or fixed a bracket, 10, onto which the hook 11 catches when the rod D is shoved up, and by which the electrodes are kept apart 20 when the lamp is not in use.

The base M' of the lamp is connected to the frame L by means of rods R R, insulated at I', I'', and I'''. In the base-piece M are set two circular plates, O and P, having shoulders, as 25 shown. The plate P is set eccentrically in O, and O is set centrally in M', the two being held by a plate, N, and screws l l. The tube R', carrying the lower-carbon holder H'' and carbon C', is set centrally in the plate O, and on 30 the under side of these plates O and P are projecting pins t t, to which a wrench can be applied to adjust the plates with reference to each other. By means of this device the lower carbon, C', can be adjusted to center exactly 35 under the upper carbon. The arrangement is fully shown in Figs. 2 and 3. The tube R' is of course fastened in the plate P, and swings with it in the plate O, the two plates being adjustable with reference to each other, by 40 which the carbon point is brought in its proper position.

The glass globe G' is held by a plate, Q, slipped on the tube R', and held by a set-screw, S', the stopper T being removable to allow the 45 plate to be slipped onto the tube in the manner shown. By these means the globe can be adjusted over the carbons to the desired position, and can be readily removed to take out one carbon and put in another.

50 The electrical connections are as follows: The main-circuit conductor comes to the binding-posts p" p''. The current enters at the + points and divides, one part passing through magnet A' to E, rod D, carbons C', base M', rod R, wire Z, to — point at p'', the other parts going through X, contact-points S''' and X', to magnet A, through magnet A and X'' to the — point through Z and Y'', thus making two closed circuits—one through magnet A' and the 55 lamp, the other through magnet A and the terminal of the lamp, the magnet A being cut out when the lamp is not in action by the contact-points S''' and S'', which takes place the instant the circuit in the magnet A is broken, by 60 which the core B is released and the lever G dropped, by which the point S'' is brought in

contact with the point S''', short-circuiting both the lamp and magnet A.

The action of the lamp is as follows: The current enters at the + point and divides, 70 one part going through and energizing the magnet A', thence through the carbons and R to the — side. This causes the magnet A' to draw in the core B' and lift the lever G. As G is lifted, the weight M causes the lever F to fall 75 and clutch the rod D between the cam e and the side of the hole in G, and as the core B' continues to lift the rod D, held by the cam-lever F, the carbon points are separated and the arc established. The other part of the 80 current passes to S''', through the coil of the magnet A, through wire X'', contact S'', wire Y'' and Z, to — point, thus also energizing the magnet A, which tends to pull in the core B; but as A' is of very low resistance and A of 85 very high resistance, the magnetism of A' overcomes that of A, and the lever G is lifted against the pull of the latter magnet. Before the lever G is lifted the current is short-circuited around the magnet A of the contact-points S''' and S''; but as soon as the lever G is lifted by the core B' the contact between the points S''' and S'' is broken, and the current passes through the coil of the magnet A, thus 90 making a continuously-closed circuit through 95 each magnet when the lamp is in operation—one of high and one of low resistance—and both of which continue closed during the normal operation of the lamp. Now, as the arc increases in length, the resistance increases in the circuit through the lamp, thus decreasing the magnetism of A', while that of A increases, thus varying the pull on the lever G, which gradually falls until the weight M comes in contact with the set-screw S', by 100 which the cam e is made to release the rod D, and allow it to fall sufficiently to re-establish the proper length of arc. The lever e is then again instantly raised, and the cam clutches and holds the rod as before. All of these 105 movements are of course gradual, so that the rod G really continually falls slowly as fast as the carbons are consumed.

In case it is desired at any time to cut a lamp out of circuit, the upper-carbon rod D 110 is pushed up until the hook 11 catches on the bracket 10, by which the circuit is disrupted, the current then going through the contact-points around the magnet A to the next lamp in circuit.

Having thus described my several improvements in arc-lights, I claim and desire to secure by Letters Patent the following claims:

1. In an arc electric lamp, the combination, 115 with the upper-carbon rod, of a rocking lever, G, two moving magnet-cores, B and B', a weighted cam-lever, F, contact-points S''' and S'', and differential magnets A and A', electrically connected in circuit, and coacting, substantially as described, to govern the operation of the lamp.

2. In an arc electric lamp, the combination

of two electro-magnets, one being of high resistance, and the other being divided into sections and of low resistance, and both being connected in the circuit of the lamp, combined with moving magnet-cores and a rocking lever having elongated pivot-holes $P' P''$ P''' , and clutch F , common to both of them, and also with the upper-carbon rod, for the purpose of operating the same.

5 10 3. In an arc electric lamp, the combination, with the upper-carbon rod, of a rocking lever embracing said rod, and holding a cam-lever impinging against it, and a positive weight upon said cam-lever, the weight and cam-lever coacting with the embracing-lever to hold and feed the rod, as described.

15 20 4. In an arc electric lamp, the combination, with the lower-carbon rod or holder, of adjusting-pieces $O P$, having shoulders, and one being set eccentrically in the other in the base of the lamp, for the purpose of centering the carbons, substantially as described.

5. In an arc electric lamp, the combination, with the lower-carbon rod, of a tubular holder and an adjustable globe-holder, Q , clamped 25 to the said tubular holder below the lamp-frame, by means of which the globe is readily slid up and down or removed to facilitate the placing of the carbons.

6. In an arc electric lamp, the upper-carbon 30 rod or holder D , provided with a bracket, 11 , and a hook, 10 , to engage in said bracket, in combination with differential magnets A and A' , magnet-cores B and B' , lever G , and contact-points S''' and S'' , connected in the circuits 35 of an electric lamp, substantially as described, for the purpose specified.
